Office Action (Notice of Allowance) dated Dec. 28, 2018, by the Taiwanese Patent Office in corresponding Taiwanese Patent Application No. 107302831. (3 pages).

Primary Examiner — John Windmuller

(74) Attorney, Agent, or Firm — Buchanan, Ingersoll & Rooney PC

(57) **CLAIM**

The ornamental design for a spring for a sprinkler head, as shown and described.

DESCRIPTION

FIG. 1 is a front elevational view of a spring for a sprinkler head showing my new design, a rear elevational view thereof being a same image;

FIG. 2 is a right side elevational view thereof; a left side elevational view thereof being a same image;

FIG. 3 is a top plan view thereof; and,

FIG. 4 is a bottom plan view thereof.
